HOLDER FOR A TEMPLATE AND A PUNCHABLE CARD

John W. Whitson, 120 Cabrini Blvd., New York, N.Y.

Filed Dec. 11, 1964, Ser. No. 82,989

Term of patent 14 years

(Cl. D64—11)

FIG. 2

FIG. 1

FIG. 3

FIG. 1 is a top plan view of a holder for a template and a punchable card showing my new design.

FIG. 2 is a sectional view taken on line 2—2 of FIG. 1.

FIG. 3 is a sectional view taken on line 3—3 of FIG. 1.

I claim:

The ornamental design for a holder for a template and a punchable card, as shown.
